UNITED STATES PATENT OFFICE.

CHRISTOPHER RICHARDSON, OF NEWARK, NEW JERSEY.

SAW-HANDLE.

SPECIFICATION forming part of Letters Patent No. 320,169, dated June 16, 1885.

Application filed September 15, 1884. (No model.)

To all whom it may concern:

Be it known that I, CHRISTOPHER RICHARDSON, a citizen of the United States, residing in Newark, Essex county, New Jersey, 5 have invented certain new and useful Improvements in Combination Saw-Handles, fully described and represented in the following specification and the accompanying drawings, forming a part of the same.

10 This invention consists in a special construction for the handle of a hand-saw, whereby it is provided with several grooves, bolt-holes, and a removable clamping-bolt adapted to fit such holes, and to hold various kinds of saw-blades in different positions relative to the handle.

It also consists in the combination, with a longitudinal groove, of pins inserted through the wood across the bottom of the groove to 20 sustain the pressure of the saw-blade. A modification of the same also includes the use of two longitudinal grooves and two holes through the head for the clamping-bolt.

In the drawings, Figure 1 is a side view of 25 the handle with a pruning-saw, S, clamped in the bottom longitudinal groove, D. Fig. 2 is an end view of the same construction without the saw-blade, the alternative longitudinal groove F being shown at the right-hand side 30 in both these figures, and also in Fig. 3, which is a plan of the handle, with a compass-saw, S', inserted in such side groove. Fig. 4 is a plan, and Fig. 5 an end, view of the handle constructed without such side groove, and 35 having a key-hole saw, S", clamped in the transverse groove E.

A is the shank of the saw-handle of the usual hooked shape employed with hand-saws intended for use in one hand, and formed with 40 a head, B, projecting forward at right angles from the handle to receive the saw-blade. C is a bolt-hole inserted through the head parallel with the shank of the handle, and D and E are respectively longitudinal and transverse 45 grooves, both formed in the head upon the inner side and intersecting the hole C. C is a bolt inserted through the hole C, and provided upon its inner end with a slot or hook to receive the saw-blade, and upon its outer 50 end with a nut, G, to draw such hook or slot toward the bottom of the grooves.

In Figs. 1, 2, 4, and 5 the clamping-bolt C is shown inserted through a vertical hole, C', which appears in the top of the handle, as seen in Fig. 3; but in the latter figure the bolt is 55 inserted in a transverse hole, C', which is indicated in Figs. 1 and 4. The grooves D, E, and F extend about half-way through the head B, as shown in the drawings, the outer side of the head next the thumb-nut G (shown in Fig. 60 1) not being weakened by any perforation except the bolt-hole C'.

A second feature of my invention consists in the insertion of metallic pins *x x* through the head of the handle at the bottom of the 65 longitudinal groove D. These pins are employed chiefly to sustain the back of the saw in contact with the longitudinal fibers of the wood, which do not resist the wear and jar-ring of the blade so well as when the groove 70 is formed across the grain of the wood, as at E. If riveted over at the ends, the pins also serve to strengthen the head of the handle where it is intersected by the grooves D and E. When the groove F is formed in one side 75 of the head in conjunction with the other grooves, the corner piece on that side of the head is cut entirely out, so that the blade and part of the bolt C are exposed, as seen in Fig. 1, where the letter E is placed; but 80 the latter is sufficient to sustain the blade, as the inner end of it is fully inclosed in the groove F. By these constructions the handle is adapted for holding several kinds of blades in a variety of positions, and thus doing many 85 kinds of work for which several separate tools would otherwise be required. It is also adapted to fit any blades ordinarily found in stores or on sale.

I am aware that it is not new to provide a 90 crosscut-saw handle with a metallic plate having grooves arranged at right angles to vary the application of the handle to the saw-blade, and that fret-saw and other handles have been made to hold the saw in different positions; 95 but I am not aware that any hooked handle constructed like that shown herein with a shank, A, and a head, B, projected forward at right angles thereto has been provided with a clamping-bolt inserted through the head at 100 the intersection of two or more saw-grooves, in the manner herein set forth. I do not there-

fore claim, broadly, the combination of a saw-handle with grooves disposed at different angles, but only the combination of the clamping-bolt and grooves, arranged, as described, 5 with the head of the hand-saw handle on its hooked shank, substantially as herein shown.

I am also aware that a grooved metallic plate applied to a wooden saw-handle to sustain the saw is a means of protection to the 10 woody fibers in the same sense as the pins $\alpha\alpha$, and I therefore only claim the particular construction and insertion of the latter in the wood transversely to the bottom of the groove.

Having thus described my invention, I claim 15 the same as follows:

1. The combination, with the handle-head having grooves D, E, and F, arranged as described, of the hole C', formed at the inter-

section of the grooves D and E, the hole C², 20 formed across the groove F, and the removable bolt C, adapted to fit either of the holes C' or C², and to clamp a saw-blade in either of the three slots, all substantially as herein shown and described.

2. The combination, with the wooden handle-head and the groove for the saw-blade, of the pins $\alpha\alpha$, inserted in the wood transversely at the bottom of the groove, as and for the 25 purpose set forth.

In testimony whereof I have hereunto set 30 my hand in the presence of two subscribing witnesses.

CHRISTOPHER RICHARDSON.
